CLAIM

The ornamental design for a frame for TV set, as shown and described.

DESCRIPTION

The claimed frame for TV set is a structure for enclosing a TV set.

FIG. 1 is a front elevational view of a frame for TV set showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.
